UNITED STATES PATENT OFFICE

107,418

DESIGN FOR A FISHING SINKER

John E. Ganaway, Fort Smith, Ark.

Application June 21, 1937, Serial No. 69,967

Term of patent 3½ years

To all whom it may concern:

Be it known that I, John E. Ganaway, a citizen of the United States, residing at Fort Smith, in the county of Sebastian and State of Arkansas, have invented a new, original, and ornamental Design for a Fishing Sinker, of which the following is a specification, reference being had to the accompanying drawing, forming part thereof.

The drawing is a view in elevation of a fishing

sinker showing my new design, the characteristic features of which reside in the formation of a coil wherein the relatively flat convolutions of the coil are slightly concaved on one side and of progressively smaller width towards each end thereof.

I claim:

The ornamental design for a fishing sinker, as shown and described.

JOHN E. GANAWAY.
